TABLE ATTACHMENT FOR LAWN CHAIRS
David W. Mohror, 309 S. Union, Rock Rapids, Iowa
Filed Aug. 17, 1960, Ser. No. 50,117
7 Claims. (Cl. 297—171)

This invention relates to an attachment particularly, although not necessarily, for lawn chairs of the vertically oscillating or rocking type comprising tubular arms integral with the upstanding legs of a generally U-shaped, stationary, resilient metallic base, and has for its primary object to provide, in a manner as hereinafter set forth, readily removable side table which is adapted to be expeditiously mounted for use on one of the arms of such chairs without altering the same structurally and, further, without extraneous securing means.

Another very important object of the present invention is to provide a table attachment for chairs of the aforementioned character which will maintain a level or horizontal position at all times.

Still another important object of the invention is to provide a table attachment of the character set forth which may be readily adjusted for use on various chairs.

Other objects of the invention are to provide a table attachment for chairs which will be comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view, showing an attachment embodying the present invention mounted on a chair;

FIGURE 2 is a view in side elevation thereof;

FIGURE 3 is a front elevational view;

FIGURE 4 is a bottom perspective view of the device per se with portions omitted;

FIGURE 5 is a detail view in perspective of one of the resilient clips, of which there are four;

FIGURE 6 is a detail view in perspective of the slideable sleeve which, in conjunction with a clip such as that shown in FIGURE 5, slidably connects the rear end portion of the chair arm to the upper end portion of the panel supporting leg;

FIGURE 7 is a detail view in perspective of the socket which receives the upper end of the panel supporting leg;

FIGURE 8 is a view in transverse section on an enlarged scale, taken substantially on the line 8—8 of FIGURE 2;

FIGURE 9 is a fragmentary view in transverse section on an enlarged scale, taken substantially on the line 9—9 of FIGURE 2; and

FIGURE 10 is a perspective view of the telescopic panel supporting leg.

Referring now to the drawings in detail, it will be seen that reference numeral 11 designates generally a conventional lawn chair of the resilient, vertically oscillating type. The chair 11 includes the usual generally U-shaped horizontal base 13 of suitable resilient metal from the end portions of which legs 14 extend upwardly. The legs 14 terminate in rearwardly extending arms 15. The members 13, 14 and 15 of the chair 11 comprise a single length of tubing. Mounted in the frame structure defined by the members 13, 14 and 15 is a seat 16 and a back 17.

The embodiment of the present invention which has been illustrated comprises an elongated plate or panel 18 of suitable dimensions and material which is mounted longitudinally on one of the chair arms 15. The panel 18 is substantially rectangular with the exception that the

2

outer, rear end portion of said panel is cut away or recessed as indicated at 19. Secured beneath the inner longitudinal marginal portion of the panel 18, adjacent the forward end thereof, is a resilient clip or clamp 20 which is engageable with the forward end portion of the chair arm for detachably securing said panel thereof. The clip 20 is generally C-shaped, as shown to advantage in FIGURE 5 of the drawings, and said clip includes in-turned end portions providing opposed jaws 21 which receive the chair arm therebetween and frictionally grip the same. The bight portion of the clip 20 is provided with an aperture or hole 22 which accommodates a screw for securing said clip beneath the panel 18.

Mounted beneath the outer longitudinal marginal portion of the panel 18, also adjacent the forward end thereof, is a depending bracket 23. A brace 24 has one end pivotally secured to the bracket 23, as indicated at 25. At its other end, the brace 24 terminates in an angularly bent eye 26 having pivotally secured thereon a clip 27 which is similar to the clip 20. The clip 27 is engageable with the chair leg 14 at a point above but adjacent to the seat 16 for detachably connecting the brace 24 to said leg.

Secured beneath the rear end portion of the panel 18, adjacent the inner longitudinal edge thereof, is a socket 28. As shown to advantage in FIGURE 9 of the drawings, the socket 28 is for the reception of the upper end portion of a longitudinally extensible and contractible supporting leg 29 for the rear end of the panel 18. The leg 29 comprises telescopic upper and lower male and female sections 30 and 31, respectively, which are secured in adjusted position through the medium of a setscrew 32. At its lower end, the female section 31 of the telescopic leg 29 terminates in a right angularly bent eye 33 having secured therebeneath a resilient clip 34, which is also similar to the clip 20, for detachably securing the lower end of the leg 29 on the adjacent leg of the generally U-shaped chair base 13. This is shown to advantage in FIGURE 8 of the drawings. The upper end portion of the male section 30 of the leg 29 is engaged in the socket 28.

A coupling 35 connects the upper end portion of the leg 29 to the rear end portion of the chair arm 15 on which the panel 18 is mounted. The coupling 35 comprises a sleeve 36 which is slidable on the upper end portion of the male section 30 of the leg 29. Mounted on the sleeve 36 is an arm 37 (see FIGURE 6), said arm having secured thereto a clip 38 which is engaged with the chair arm 15. Thus, the leg 29 is connected to the chair arm in a manner to permit vertical swinging movement of 50 said arm.

It is thought that the operation of use of the device will be readily apparent from a consideration of the foregoing. Briefly, the device is expeditiously mounted on the chair by simply snapping the resilient clamps or clips 20, 27, 34 and 38 on the respective members of said chair. The front end of the panel 18 rests on the chair arm and the outer portion thereof is supported by the brace 24. However, the rear end of the panel 18 is free of the chair arm and supported by the leg 29. Accordingly, it will be seen that the leg 29 maintains the panel 18 in a substantially horizontal position independently of the chair arm 15, permitting said arm to move vertically as when the chair is first sat in or oscillated by the occupant. As will be readily apparent, the telescopic leg 29 facilitates leveling the panel 18 for use on different chairs and to meet various conditions. With the leg 29 mounted on the base 13 the chair 11 may be readily moved from place to place with the table attachment mounted thereon.

The foregoing is considered as illustrative only of the principles of the invention. Further, since numerous modifications and changes will readily occur to those skilled in the art, it is not desired to limit the invention to

the exact construction and operation shown and described, and accordingly all suitable modifications and equivalents may be resorted to, falling within the scope of the invention as claimed:

What is claimed as new is as follows:

1. For attachment to a vertically oscillating chair of the type including a base, a resilient leg extending upwardly from the front portion of said base and a rearwardly extending arm on the upper end portion of said leg, a table comprising a panel mounted longitudinally on the arm, means securing the forward end portion of said panel to the corresponding end portion of said arm, a supporting leg mounted beneath the rear end portion of the panel, and means slidably connecting the rear end portion of the arm to the upper portion of said leg.

2. For attachment to a vertically oscillating chair of the type including a base, a resilient leg extending upwardly from the front portion of said base and a rearwardly extending arm on the upper end portion of said leg, a table comprising a panel mounted longitudinally on the arm, means securing the forward end portion of said panel to the corresponding end portion of said arm, a supporting

and means slidably connecting the rear end portion of the arm to the upper portion of said leg, said means including a clip removably mounted on the arm, and a sleeve secured on said clip and slidable on the leg.

5. For attachment to a vertically oscillating chair of the type comprising a base, a resilient leg extending upwardly from the front portion of said base and a rearwardly extending arm on the upper end portion of said leg, a table comprising an elongated panel mounted longitudinally on the arm, a resilient clip beneath the forward end portion of said panel engageable with the corresponding end portion of the arm for removably securing said

panel thereto, a brace pivotally secured beneath the forward end portion of the panel, a resilient clip on one end of said brace engageable with the leg for detachably connecting said brace thereto, a socket mounted beneath the

5 rear end portion of the panel, a supporting leg for said rear end portion of said panel having its upper end engaged in said socket, and means for slidably connecting the rear end portion of the arm to the upper end portion of the second-named leg.

10 6. For attachment to a vertically oscillating chair of the type comprising a base, a resilient leg extending upwardly from the front portion of said base and a rearwardly extending arm on the upper end portion of said leg, a table comprising an elongated panel mounted longi-

15 titudinally on the arm, a resilient clip beneath the forward end portion of said panel engageable with the corresponding end portion of the arm for removably securing said panel thereto, a brace pivotally secured beneath the for-

ward end portion of the panel, a resilient clip on one end 20 of said brace engageable with the leg for detachably connecting said brace thereto, a socket mounted beneath the rear end portion of the panel, a supporting leg for said

rear end portion of the panel, a supporting leg for said rear end portion of said panel having its upper end en-

gaged in said socket, and means for slidably connecting

25 the rear end portion of the arm to the upper end portion of the second-named leg, said means comprising a resilient clip removably mounted on the arm, and a sleeve mounted on the second-named clip and slidable on the second-named leg.

7. For attachment to a vertically oscillating chair of the type comprising a base, a resilient leg extending upwardly from the front portion of said base and a rearwardly extending arm on the upper and forward portion of said base, a resilient clip having a panel rotatable longitudinally on the arm, a resilient clip beneath the forward end portion of said panel engageable with the corresponding

on the second-named clip and slidable on the second-named leg, said second-named leg including adjustable, telescopic male and female sections, said second-named

50 telescopic male and female sections, said second-named leg further including a clip on its lower end engageable with the base for removably mounting said second-named leg thereon.
